JOHN S. FIFIELD, OF WESTERLY, RHODE ISLAND.

Letters Patent No. 65 736, dated June 11, 1867.

COAL-SIFTER.

The Schedule referred to in these Letters Patent and making part of the same.

TO ALL WHOM IT MAY CONCERN:

Be it known that I, J. S. FIFIELD, of Westerly, in the county of Washington, and in the State of Rhode Island, have invented certain new and useful improvements in Coal Buckets for Sifting the Coal and Ashes; and do hereby declare that the following is a full, clear, and exact description thereof, reference being had to the accompanying drawings and to the letters of reference marked thereon.

In the annexed drawings, making part of this specification, A represents a box, which is provided with a movable top B', a drawer C, and a doorway at D. The cover B' is provided with a hinged door, B. E represents a wheel, which is formed of two annular plates placed at a proper distance apart and covered with gauze wire, the gauze wire forming the periphery of the wheel. The wire does not extend entirely around the wheel, but partially so, leaving a doorway. A shaft, F, passes through the centre of this wheel from side to side, and has its bearings in the sides of the box A. G represents a partition which is placed in the wheel E, extending from one edge or side of the doorway into the wheel in the direction represented, and having its inner end turned in slightly. Beneath the wheel E is placed an inclined sieve, H, which leads to the doorway at D. Beneath the sieve is placed a drawer, C, which is intended for catching the ashes as they fall from the coal cinders. In using this machine, the door B is lifted, and the coal cinders are poured into the wheel E through its doorway. The wheel E is then removed so that the cinders will strike against the partition G, which throws them back upon the gauze-wire periphery of the wheel. The coal cannot leave the wheel E as long as the said wheel is revolved, so that it will strike the partition G, and is consequently carried around and around in the wheel until thoroughly cleansed of ashes. The ashes as they leave the cinders fall through the gauze-wire screen and through the screen H into drawer C. When the cinders have been properly sifted, the wheel E has its motion reversed, and they run out of the opening in the wheel and fall upon screen H, and thence pass out of the box through door at D.

Having thus fully described my invention, what I claim is—

The arrangement of the box A with wheel E, as constructed, sieve H, spout D, and drawer C, in the manner and for the purposes substantially as set forth.

In testimony that I claim the foregoing, I have hereunto set my hand and seal this twentieth day of February, 1867.

JOHN S. FIFIELD.
